MUSICAL INSTRUMENT STAND
Sidney A. Greenspan, 8236 Christina Ave., Skokie, Ill.
Filed Apr. 29, 1963, Ser. No. 276,526
1 Claim. (Cl. 248—170)

My invention relates to new and useful improvements in musical instrument stands and has for its object the provision of an improved structure of the character hereinafter described which will be highly efficient in use and economical in manufacture.

While my invention is shown as a drum support, it is to be understood that it is not to be so limited. A principal object of the invention is to provide an instrument-supporting stand which may be adapted to support a variety of sizes of instruments of the type for which it is constructed, with firmness and rigidity and in a manner such that the instrument will not vibrate or bounce when being played.

Another and equally important object of the invention is to provide in a musical instrument stand a standard which may be folded relative to a base when moved from and into instrument-supporting position. In such an instrument stand, it is essentially necessary that when the standard is folded with respect to the base in instrument-supporting position, that it be substantially rigid and restrained from vibrating during playing of the instrument. It is therefore one of the objects of this invention to provide a simple arrangement for effecting rigidity between the base and the standard when the latter is folded relative to the base into instrument-supporting position.

In a musical instrument stand for the character herein-after described, the supporting head of the stand is generally provided with radially disposed arms which are mutually brought together when the supporting head is in collapsed position and folded in parallel relationship with respect to the standard of the stand. It is an object of this invention to mount one of the instrument-holding arms in a manner such that it may be yieldably adjusted to accommodate the head of the stand to the size of the instrument to be held thereon and to bear against the instrument under spring action so as to firmly yieldably hold the instrument upon and within the arms of the head.

Other objects will appear hereinafter.

The invention consists in the novel combination and arrangement of parts to be hereinafter described and claimed.

The invention will be best understood by reference to the accompanying drawings showing the preferred form of construction, and in which:

FIG. 1 is a perspective view of a musical instrument stand having incorporated therein my invention, the stand being shown in folded position;

FIG. 2 is a perspective view of my musical instrument stand showing the same in extended position;

FIG. 3 is a sectional detail view taken substantially on line 3—3 of FIG. 5;

FIG. 4 is a fragmentary sectional detail view taken substantially on line 4—4 of FIG. 3;

FIG. 5 is a plan view taken substantially on line 5—5 of FIG. 3;

FIG. 6 is a sectional detail view taken substantially on line 6—6 of FIG. 2.

The various objects of my invention are preferably accomplished by the preferred form of construction shown in the accompanying drawings and which will now be described. In this connection, the musical instrument stand embodying my invention comprises a base 10, a standard 11, and a head 12. The base comprises two circularly formed discs 13 and 14 spaced from each other and secured together by pins 15 two of which serve as pintles for the movable legs 16 which have their inner end por-

2

tions 17 disposed between the discs 13 and 14. A third leg 18 has its end portion 19 disposed between the discs 13 and 14 and rigidly secured thereto by the remaining two pins 15.

5 The outer end portions of each of the legs 16 and 18 carry caps 20 formed of plastic or other material and which serve to prevent marring or scratching the surface upon which the instrument stand is placed.

Secured by spot welding 21 or other means to the disc 14 are brackets 22 angled to provide parallelly extending upright plates 23. The standard 11 comprises telescopically arranged sections 24 and 25 secured together in an adjusted position with respect to each other by means of a suitable wing nut and bolt 26. The lower end portion 27 of the section 24 projects between the plate 23. This end portion 27 of the section 24 is slotted longitudinally as at 28. Projecting through the slotted portion 28 is a horizontal pin 29 carried by the plates 23. Press-fitted into the end portion 27 is a detent 30, the end of which extends beyond the slotted end portion 27 of the section 24 of the standard and is adapted to engage an opening 31 formed in the plate 14.

The outer end of the detent 30 is chamfered as at 32 to facilitate its movement into and out of the opening 31. Positioned between the pin 29 and the detent 30 is a spring 33.

25 The arrangement is such that to withdraw the detent 30 from the opening 31, the section 24 of the standard 11 is pulled upwardly relative to the plates 23 against the action of the spring 33. When the detent 30 is clear of the opening 31, the standard may be pivoted relative to the disc 14 into the position shown in FIG. 1. This is accomplished after the movable legs 16 have been pivoted in substantially parallel position with respect to the stationary leg 18. When the standard 11 is pivoted to an extended position relative to the disc 14, the spring 33 acting upon the detent 30 and pin 29, will serve to project the detent 30 automatically into the opening 31, in which position the detent 30 will rigidly support the standard 11 in extended position with respect to the disc 14.

30 The outer end portion 34 of the section 25 of the standard 11 is positioned between the oppositely disposed elongated plates 35. These plates 35 are of similar size and shape.

35 The corresponding lower end portions of the plates 35 are connected to the end portion 34 by a wing nut bearing bolt 36. Between the end portion 34 of the section 25 and the corresponding end portions of the plates 35 are arranged brackets 37, which, together with the opposite corresponding end portions of the plates 35 are connected to the end portion 34 of the section 25 by a rivet 38. The brackets 37 have angled end portions 39. Mounted on these end portions 39 is a circular disc 40. Positioned on the disc 40 is an outer disc 41 spaced from the disc 40. Between these discs 40 and 41 are positioned the end portions 42 of pivoted arms 43, the end portions of which are angled upwardly to provide plastic-covered jaws 44 which bear against the instrument 45 being supported by the stand.

40 Positioned between the discs 40 and 41 is an elongated channel-shaped member 46. Slidable through this channel member in a direction longitudinally with respect to its long axis is the shank 47 of an arm 48, which, like the arms 43, has a plastic-covered jaw 49 adapted to cooperate with the jaws 44 to firmly hold therebetween the musical instrument 45. The arm 48 is yieldably restrained in its movement by a spring 50, one end of which is connected to the arm 48 and the opposite end to the brackets 37, as seen in FIG. 3.

45 The spring 50 functions normally to resist movement of the arm 48 relative to the channel member 46 and to yieldably urge the instrument 45 within the confines of the jaws 44 and 49. A stop pin 51 is carried by the

end portion of the arm 48 to limit the movement of the arm 48 in a direction against the action of the spring 50.

The form of construction shown in the drawings has proven to be highly effective for firmly holding the instrument within the confines of the jaws of the head 12 and to hold the standard 11 substantially rigid during playing of the instrument. The simple form of detent permits the standard 11 to be readily collapsed with a minimum amount of effort, with respect to the legs 16 and 18. The thumb nut-bearing bolt 36 may be adjusted to vary the tension at the pivotal connection of the head 12 with the end portion 34 of the section 25, so as to firmly hold the head 12 in an adjusted position with respect to the standard 11.

The arms 43, as well as the legs 16, are free to swing about their respective supports, but will stay in any position to which they are adjusted. The arm 48 being adjustable relative to the discs 40 and 41, will permit the head 12 to support with firmness and rigidity a variety of sizes of musical instruments. By the use of the spring controlled slideable arm 48, the musical instrument may be quickly and easily mounted upon and removed from the head.

The simplicity of construction permits economical manufacture. The stand may be formed of such material as will best serve the purpose. A stand constructed in accordance with the foregoing description will be sturdy and yet easily and quickly foldable to a collapsed position when not in use to facilitate storage or transport.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

A collapsible musical instrument stand including an elongated standard,

- (a) a base structure pivotally connected at one end of said standard for supporting the same in a vertical plane when in an extended position,
- (b) a head pivotally connected to the opposite end of said standard upon which a musical instrument is adapted to be removably mounted,
- (c) a plurality of arms radially extending from said head and terminating at their free ends into lateral extending jaw members,
- (d) one of said arms connected to said head for radial movement relative thereto and to the other of said arms,

- (e) means for slidably connecting said one of said arms to said head,
- (f) spring means connected to said head and one of said arms for yieldably moving said one of said arms and its jaw member radially with respect to said head and said other jaw members provided by said other arms,
- (g) said other of said arms connected to said head for angular movement through a horizontal plane relative thereto and to each other,
- (h) means for pivotally connecting said other of said arms to said head,
- (i) means for connecting said head to said standard for pivotal movement about a horizontal axis and transversely to the longitudinal length of said standard for collapsibly positioning said head and said arms in a substantial parallel plane with respect thereto,
- (j) said base structure including a base plate having pivotally connected thereto a plurality of radially extending legs,
- (k) means for pivotally connecting said base structure to said standard,
- (l) said last named means including a detent carried by and extending from the lower end of said standard and removably engaging a hole provided by said base plate,
- (m) said lower end of said standard having a longitudinal slot formed therein,
- (n) a pin carried by said base plate and extending through said slot for pivotally connecting the standard to the base plate,
- (o) and a spring member within said standard interposed between said pin and said detent, said detent being removable from projection into said opening by movement of the standard longitudinally of its axis against the action of said spring member so that said base plate and said legs may be pivoted about said pin into a substantial parallel relation with respect to said standard and said head when the same is in a collapsible position.
